ABSTRACT OF THE DISCLOSURE

The present invention relates to a control device for movable thread guide devices such as harnesses of looms which are moved by an associated rotating eccentric cam with the interposition of an associated transmission element, the effective length of which may selectively be changed and is an improvement of the device shown in 15 said copending application Ser. No. 575,297.

This application is a continuation-in-part of copending application Ser. No. 575,297, filed Aug. 26, 1966, now 25 U.S. Patent No. 3,410,314.

In looms having, for instance, harnesses as thread guiding devices in which the movement of the harnesses is effected by cams, it is necessary to provide a separate cam for each individual harness. Where each weave pattern requires a separate cam arrangement, with each change of the weave pattern, the entire cam arrangement must be rearranged, which is extremely time-consuming. Furthermore, in most cases when the pattern is changed, not only must the cams be rearranged, but they must also be replaced by cams having different cam surfaces.

It is therefore necessary, in order to have the possibility of making different patterns, to keep in stock a large number of cams provided with different cam surfaces. Furthermore, it is to be noted that even if cams with various different cam surfaces are used, the number of designs available is limited to the cams in stock.

Looms are also known in which in order to form the weave pattern, the harnesses are moved by dobbies. In this way the disadvantage of the limited number of possible patterns is eliminated. In order to control the dobbies, cards are used which have punched holes, for example, to define a pattern and which are scanned by feeler pins. This use of dobbies to control the pattern is, however, relatively time-consuming and hence limits the operating speed of the loom so that its full capacity is not utilized.

Where the harness has a high and low position which is directly controlled by a transmission element of the type shown in copending application Ser. No. 575,297, which is arranged between the cam and the harness, where the cam turns only one-half turn with each full rotation of the drive shaft of the loom, it is not possible to cause a sequence of high and low positions in a random pattern. Thus, for example, only one rhythm of high and low position can take place where a single cam is employed. Furthermore, where a high position is repeated several times, a separate locking arrangement is required to retain the harness in its high position. Such arrangement necessarily slows down the speed of operation of the device and a device of this type is not capable of a multiplicity of random patterns.

The object of the present invention is to provide control devices for movable thread guide means of the type above described which will afford a very high degree of speed in the movement of the thread guide means or harness, according to any desired pattern with relatively simple and

readily controllable mechanism, and without need to mechanically lock the harness in the high position.

According to the invention this object is obtained by having each harness controlled by a pair of cam driven transmission elements through the intermediary of a lever which is operatively connected to the harness and the ends of which are operatively connected to an associated transmission element, the effective length of each transmission element being controllable. Depending on the effective length of each of the transmission elements, the motion impulse caused by the rotating cams will not move the corresponding thread guide or harness at all, or will move it by a maximum amount, or by one or more intermediate amounts.

In the case of a loom provided with harnesses, this means that the harnesses can be moved under the control of the transmission elements into a lower shed or an upper shed, or one or more intermediate sheds. In this way the transmission elements themselves are used to control the movement of the harnesses. It is to be noted that when changing the pattern, no cams need be changed or removed since the movement impulses coming therefrom are always governed by the effective lengths of the transmission elements which determines whether the impulses result in a change of harness motion or not.

The transmission element, according to the invention, is a pusher rod having a deformable portion and controlled in various manners so that the effective length of the rod may be adjusted in accordance with the desired position 30 of the thread guide means or harness.

According to the preferred embodiment of the invention, the deformable portion is formed by pivoted arms or links which may be moved or bent laterally outward to change the effective length of the rod.

The extent of the lateral deflection of the pivoted elements determines the effective length of the pusher rod.

The mechanism to restrain movement of the deformable portion of the rod could be incorporated into the pusher rod itself. However, it is preferred to use an arrangement in which the deformable portion will automatically bend due to the load acting on the pusher rod, produced between the driving cam and the thread guide means or harness and to restrain such bending by a movable stop. The stop which restrains the deformable portion from bending can be fully mechanical or an electric magnet can be employed to bring the stop into an active or inactive position. The stop can be alternately moved by the electromagnets into one direction or the other, and preferably movement in one direction is effected by electrical energization of the magnet while the movement in the other direction is effected by gravity or a pre-tensioned spring.

The pusher rod itself may be of various types and may consist exclusively of a bendable member. However, it is preferable that the deformable portion be intermediate the ends of the rod so that the rigid end portions can readily be guided in their longitudinal direction.

The drive cams are staggered with respect to each other and preferably two cams are associated with a single thread guide device or harness through an associated pusher rod. In this way it is possible to lift the harness by one cam when the other cam is still in the low position. The cams are preferably arranged staggered apart with uniform spacing, for instance, in the case of two cams they may preferably be 180° apart from each other.

The control command for providing a given active length of the transmission device can be effected by the known control devices for weaving machines. For example, the control command can be recorded on pattern cards, punch cards or the like. These control devices can be used in conventional manner to open and close electric circuits. Either sensing fingers can be used or photoelectric cells

can be employed. The control command which in itself consists of a very short pulse can be further controlled by an adjustable multi-vibrator circuit in order to adjust the length of the pulse.

In the accompanying drawings in which is shown one of various possible embodiments of the several features of the invention.

FIG. 1 is a front elevational view of a loom harness together with the control mechanism therefor;

FIG. 2 is a sectional view taken along line II-II of FIG. 1;

FIG. 3 to FIG. 6 are diagrammatic views showing the control mechanism in various operating positions;

FIG. 6A is a diagrammatic partial cross section of a loom;

FIGS. 7 and 8 are diagrammatic views of another embodiment of the invention in various operating positions, and

FIG. 9 is a front elevational view similar to FIG. 1 of still another embodiment of the invention.

It should first be noted that the drawings merely show sufficient mechanism necessary for a clear understanding of the invention;

The type of loom in which the invention can be incorporated could utilize a shuttle or be a shuttleless loom.

In FIGS. 1, 2 and 6A, the control mechanism according to the invention is shown in connection with a weaving loom of conventional type. Only one harness 10 is illustrated although it is understood that conventional looms have a plurality of harnesses 10 which serve to guide the thread in conventional manner.

The harness 10 has a series of heddles 11 through the holes or eyes 12 of which the warp threads 15' extend in conventional manner to be guided thereby.

Each harness 10 is reciprocated vertically as indicated by the arrows 13 by the control mechanism to be described. Each harness 10 is vertically guided in parallel slides mounted on the guide 14.

Referring to FIG. 6A, the loom also includes a takeup roller 16' which takes up the finished web formed from the warp threads 15'. On the side of the warp threads 15' there is arranged disc 17' which is rotatably supported on a vertical shaft. The disc 17' serves in known manner together with other generally eccentrically arranged supports to effect movement of a filling needle (not shown) which carries the filling threads. A reed 18' associated with the warp threads operates in conventional manner.

In the normal operation of the loom, the harnesses 10 are moved up and down according to the desired weave pattern.

As illustratively shown, the loom has a high and low position. In FIG. 1 the harness is shown in its low position. All of the harnesses are driven through a suitable transmission from the drive shaft of the loom, which shaft rotates a pair of eccentric cams 15 and 16 which control an associated harness 10.

As each harness has its own control mechanism, it will be sufficient for purposes of understanding the invention, to describe a single control mechanism such as shown in FIG. 1 for example.

The control mechanism for each harness desirably includes two pusher or lifting mechanisms 17 and 18. The pusher or lifting mechanisms 17 and 18 are designed to be adjusted in length to at least two different sizes by the deformation or kinking of linked parts. These sizes result in corresponding harness positions, for instance, a low position and a high position. As will hereinafter be described in detail, the control can be effected by means of a control device 19 in such manner that all known types and patterns of weave can be created.

As previously stated, the motion impulse of the harnesses is derived from the main drive shaft of the loom and the main drive shaft normally actuates the two

eccentric cams 15, 16 with a reduction ratio of two to one.

In the embodiment shown in FIG. 1, two cam shafts 20 and 21 are provided, each of which carries an eccentric cam 15 and 16 arranged 180° apart. The cams 15 and 16 are movable in tracks 22 and 23 in which guide rollers 24, 25 are positioned. The rollers 24, 25 mount lower push rods 26, 27 which are positioned in suitable guides or bearings 28 for vertical reciprocation of such push rods.

Pivots connected to the free end of each of the push rods as at a, is a link 32, 34, each of which is pivotally connected between its ends as at 32', 34' to the corresponding portion of a second link 33, 35, each pair of links 32, 33 and 34, 35 defining the deformable or flexible regions 30, 31 respectively.

The free end of each of the links 33, 35 is pivotally connected as at b, to the lower end of an upper push rod 26', 27', the latter being slidably mounted in suitable upper bearings 28 aligned with the lower bearings 28 for longitudinal guidance of such upper push rods 26', 27'.

It is to be noted that in the absence of any restraint, when the associated lower push rods 26, 27 are reciprocated by the associated cams and cam rollers 15, 24 and 16, 25, due to the deformation of the links 30, 31, no motion will be imparted to the upper push rods 26', 27'.

The upper end of each of the push rods 26', 27' protruding from the associated upper bearing 28 carries an associated support 41, 42 to which the ends of an actuating lever 38 are pivotally connected as at 36, 37. The lever is pivotally connected as at its mid point as at c to a tongue 39 depending from an associated harness 10. Connected to the lower end of tongue 39 at its pivot c is one end of a coil spring 40, the other end of which is secured to a fixed support d so that the coil spring 40 will normally urge the harness 10 downwardly to its low position.

Positioned on each side of the deformable link portions 30, 31 is an associated slide assembly 43, 44, each of which comprises a movable slide 45, 46 and an associated fixed member 47, 48. In order to change the position of the movable slides 45, 46, an associated electromagnet 49, 50 is provided.

Each of the slides 45, 46, in the illustrative embodiment is movable between two positions. In the position of the slide 46 shown on the left side of FIG. 1, the slide 46 will be in a path of movement of the mid portion of links 34, 35 to retain the latter in their extended position. In the position shown on the right side of FIG. 1, the slide 45 will be displaced from the path of movement of the mid portion of links 32, 33 so that the latter may flex or deform to their collapsed position shown.

Thus, in the position of the slide 45 shown in FIG. 1, since the links 32, 33 are free to pivot relatively to each other, vertical movement of push rod 26 will have no effect on the position of upper push rod 26'.

The sideway movement of the slides 45, 46 is illustrated by the double headed arrow 51 shown in FIG. 2. This sideway movement is accomplished by means of the solenoid of the associated electromagnet 49, 50.

Desirably, the motion is uni-directional in that when the electromagnet is energized the associated slide 45, 46 is positively moved forward, say to the position of the slide 46 shown in FIG. 1 to prevent flexing of the deformable portion 31 of the assembly. When the electromagnet is de-energized, a spring (not shown) retracts the slide, say to the position of the slide 45 shown in FIG. 1.

Control of the electromagnets is effected by the control device 19. In the illustrative embodiment such device comprises a punched roll, card or tape arrangement 52, the punched holes corresponding to the desired weaving pattern. On one side of the punched card or tape 52 is 75 a source of light 53 and on the other side is a light sensi-

tive device such as a photocell 54. If there is a hole in the card or tape 52 between the source of light 53 and the photocell 54, the photocell 54 will be energized and an electric current will be created which is fed through lead 55 to an amplifier 56 and then through lead 57 to the electromagnet 49, for example, to actuate the latter at desired intervals. A similar light source and photocell 53, 54 and associated amplifier 56 is provided for the electromagnet 50.

Referring to FIGS. 1 and 2, inasmuch as cam 15 is already in the high position, and during one rotation of the loom drive shaft, because of the previously mentioned speed reduction of two to one, moves with one-half speed with respect to the loom drive shaft, during the next pick of the loom the cam 15 will move to its low position where the cam 16 is located and will then again reach its high position on the next pick.

In order to obtain a high position of the harness during the next following pick position, the harness 10 through its linkage 27, 27' must be placed in the high position. This cannot be accomplished by the push rods 26, 26' during the next following pick, because of the form of the cams and the speed of rotation and can only take place in the pick following the next pick.

In order that the push rods 27, 27' can produce a high position of the harness in the future, the flexible portion or linkage 31 must be stiffened.

This requires that the punch card or tape 52 and the electromagnet 50 must have a hole positioned between the light source 53 and the photocell 54 so that the electromagnet 50 can be energized and the slide 46 moved to its effective position. During the now following lift position of the pusher rod 27, the interconnecting links 34, 35 will be supported by abutment against slide 45 so that they will remain in their extended position. As a result, the motion of the lower push rod 27 will cause a corresponding motion of the upper push rod 27' and the harness 10.

Inasmuch as the slide members 45, 46 are firmly supported by the fixed members 47, 48 and solely act as an abutment, the slide members may be relatively small in size and light in weight so that the magnet can also be small and can rapidly actuate the associated slide member. Furthermore, the slide need only act as an abutment for one of the link members, illustratively the lower link member 32, 34 in the present embodiment which means that the slide need merely be moved the width of such link member to be out of the path of movement thereof.

It is to be noted that if the push rods 27, 27' are in their high position, and during the next following loom pick, the harness 10 is still in its high position, the slide 46 is free of forces thereagainst so that it may readily be moved to its retracted position required by the weave position.

With the arrangement above described, where two cams and two control mechanisms are employed, no locking arrangement is required to retain the harness in high position and a more versatile weaving pattern can be developed. Furthermore, through a reduction in speed of the cams with respect to the speed of rotation of the drive shaft of the loom, i.e., two to one reduction, a more quiet operation with less wear is achieved.

It is to be noted that one of the links 33, 35 has at its lower end a nose 58, 59 which serves as a support for the pair of links 32, 33 and 34, 35. This prevents a snapping over in the opposite direction of the associated pair of links when the machine is operated quickly. In other words, engagement of the nose 59 of link 35 with the link 34 limits movement of the links to the left beyond the vertical position.

In FIGS. 3 to 6 inclusive, four different positions of the control mechanism 30 is illustrated.

In FIG. 3 the cam 15 is shown in its lower position. As a result, the upper and lower push rods 26', 26

will fall to their lower position and the deformable portion 30 between the lower and upper push rods 26, 26' will be in its fully extended or stretched position.

Assuming that in the next half turn of the cam 15 the program calls for a high position of the harness 10, the slide 45 will be moved with respect to the link 32 to serve as a support therefor. Thus, if in the next half position of the cam 15, the rod 26 is lifted, motion will be transmitted through the stiffened linkage 30 to the upper push rod 26'.

In FIG. 4 the half turn has been exceeded by several degrees and the downward movement of the push rod 26 has already been initiated.

Assuming that the program for the next following motion of cam 15 calls for a low position of the harness, this can be preplanned as shown in FIG. 4 that the slide 45 is moved from its supporting position. As diagrammatically shown in FIG. 4, since the slide 45 has been moved from the supporting plate it is not shown.

In FIG. 5 the culmination point of the motion following the motion previously mentioned of cam 15 is illustratively shown. In this position the slide 46 is not shown since it is out of the plan of the drawing. Due to the collapse of the deformable portion 30, the upper member 41 of rod 26' is in its lower position which is the same as that of FIG. 3 despite the fact that the lower push rod 26 is in its high position.

Assuming that during the next following motion of the cam 15, it is desired to move the associated harness 10 to the high position, the preparation of such positioning is shown in FIG. 6. Thus, the cam 15 has already rotated approximately 30° beyond the position of FIG. 5 and the downward movement of the push rod 26 has already been initiated. The slide 45 can be moved by its associated electromagnet 49 to its locking position. It cannot assume this position at this moment since the link 32 is still in the way. However, the slide 45 can be urged toward its operative position and as soon as the link 32 is clear of the slide, the slide 45 will move to its final position to retain the linkage 30 in its extended position.

Thus, the system can readily be prepared for its next position while the equipment is operating.

In the embodiment shown in FIGS. 7 and 8, the harness (not shown) is actuated by means of lower push rod 74 and upper push rod 75, the push rod 74 being actuated by a cam (not shown) similar to cam 15. The cam is in its low position with respect to FIG. 7 and its high position with respect to FIG. 8. The lower and upper rods 74, 75 are connected by links 72, 73 pivoted together as at 77. The links are pivotally connected to the adjacent ends of the push rods 74, 75 as at 78, 79 thus defining a deformable region 65. This deformable region 65 operates in the same manner as the deformable region 30, for example, of FIG. 1. Thus, rotation of the cam will effect upward movement of the lower push rod 74 which will be transmitted to the upper push rod 75 when the deformable region is in its locked extended position as shown in FIG. 7.

The control of the deformable region is effected by means of a slide assembly 60 which comprises a fixed member 61 and a slide member 62. An electromagnet 63, which is controlled by a suitable control device corresponding to the device 19 of FIG. 1, has an armature 67 to which one end of a rod 66 is connected. The fixed member 61 is mounted on a support 64 and has a bore 61' through which the rod 66 extends. The lower end of rod 66 mounts the slide member 62 which moves on a bearing 68 carried by support 64. The slide member is normally urged downwardly by a coil spring 69 connected at one end to the rod 66 and at its other end to an arm 70 carried by the support 64.

The spring 69 normally urges the slide 62 downwardly to its inactive position with respect to the linkage 72, 73.

and in such inactive position a free space 71 is provided between the fixed member 61 and the slide 62.

The linkage 72, 73 is movable between the position shown in FIG. 7 in which it is extended, to the folded or flexed position shown in FIG. 8. Secured to member 72 is a nose or projecting portion 81. When the magnet 63 is energized and the slide 62 is moved upwardly against the force exerted by spring 69 in the direction of the arrows 80, the space 71 is closed. In this position 62' of the slide 62, the nose portion 81 reacts against the surface 82 of the slide to prevent flexure of the elements 72, 73.

With the slide 62 in the position shown at 62', if the push rod 74 is lifted, since the flexible linkage 65 is restrained from bending, the upper push rod 75 will be lifted.

It is to be noted that the lateral forces exerted by the nose 81 will be transferred through the slide 62 (at its position 62') against the bearing 68 which is carried by the rigid support 64. Consequently, the rod 66 does not bear any load. In the further upward movement of push rod 74 the surface 82 will still carry the load which will then be transferred to the surface 83 of the rigid member 61 so again the rod 66 is not under any load. Consequently, when the magnet 63 is de-energized, the spring 69 will quickly move the slide 62 downwardly to its inactive position.

If, however, when push rod 74 is raised, the elements are in the position shown in full lines in FIGS. 7 and 8, i.e., in the downward inactive position of the slide 62, the nose 81 will not have any support. As a result, the force exerted on lower push rod 74 will cause flexing of the links 72, 73 which results from the fact that the nose 81 passes through the open area 71 and the links will assume the folded position shown in FIG. 8.

If, starting from the position shown in full lines in FIG. 8, in the next cam motion, a rising motion of the harness is required, this can be initiated in the flexed position shown in FIG. 8. Thus, the slide 62 is moved from its lowermost position to its effective position shown at 62' in which the surface 82 of the slide forms a continuous plane with the surface 83 of fixed member 61. This is accomplished by energization of the magnet 63.

Although the nose 81 is apparently trapped between the slide at 62' and the fixed member 61, it can readily free itself from this position and the flexible linkage 65 can assume the position shown in FIG. 7.

Thus, starting with the position shown in FIG. 8, assuming that the slide is now in the position shown at 62', despite the fact that the magnet 63 is energized, the weight of the push rods will cause the nose 81 to ride over the top surface 84 of the slide, pushing the slide downwardly to the position shown in full lines at 62 so that the deformable portion 65 will assume its extended position as shown in FIG. 7. As soon as the nose 81 moves clear of the surface 84 the slide 62 will move back to the position shown at 62' by reason of the energized magnet 63.

It is clear therefore, that for control of the length of the deformable portion 65, the period of energization or de-energization of the magnet 63 is not important. The slide 62 can take the next desired control position even if the previously initiated position is opposite to the one desired. Thus, the future position of the deformable region 65 can be predetermined during the previous operating motion. This is extremely important because the control mechanism is designed for fast operating textile machinery where only fractions of seconds are available between the different motions.

In the embodiment shown in FIG. 9, a construction similar to that shown in FIG. 1, for example, is employed.

Thus, in an embodiment in which there are a large number of harnesses, one behind the other, in order to obtain a clear shed opening through which the filling may pass, the front harnesses have to have a lower lift than the rear harnesses.

In order readily to adjust the extent of the rise and fall of the harness, an additional lever 85 is provided as shown in FIG. 9. Lever 85 is pivotally mounted at one end as at 86 and has a tongue 39' pivotally connected at one end thereto adjacent the end 86 and pivotally connected at its other end to the lever 38' as at c'. The harness 10' has a tongue 88 connected thereto at one end and connected at its other end to one or more of the openings 87 in lever 85. For smaller lifting and lowering of the harness, the openings 87 on the left side of the lever 85 would be used and for larger raising and lowering the openings 87 on the right side would be used.

As many changes could be made in the above constructions, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. A control device for a machine having movable thread guide means comprising a harness having a plurality of heddles, a tongue depending from said harness, an actuating lever, means operatively connecting said lever to said depending tongue, cam means, means to rotate said cam means, a transmission element pivotally connected to said lever at each end thereof, each transmission element comprising a pusher rod having a deformable portion between its ends, means to vary the length of said deformable portion, each of said transmission elements being interposed between an associated cam means and the actuating lever, whereby upon reciprocation of each transmission element by rotation of the associated cam means, depending upon the setting of said deformable portion of each transmission element, the harness may be moved between a high and low position and a position intermediate of the high and low position.

2. The control device set forth in claim 1 in which said pusher rod has two end portions and two intermediate portions, each pivoted to each other and to an associated end portion, said intermediate portions defining the deformable portion, said deformable portion being movable laterally outwardly in one direction to change the effective length of said rod by the force produced between the cam and the thread guide means, and a stop associated with said deformable portion and movable into alignment therewith to restrain lateral movement thereof.

3. The control device set forth in claim 1 in which said lever is pivotally connected between its ends to said tongue.

4. The control device set forth in claim 1 in which a second lever is pivotally mounted at one end to a fixed support, said second lever having a plurality of openings 55 along the length thereof, said tongue being pivotally connected at one end to said harness and pivotally connected at its other end to one of the openings in said second lever, a second tongue is pivotally connected at one end to said actuating lever and at its other end to said second lever between the fixed pivotal mount thereof and the opening to which said tongue is pivotally connected.

5. The control device set forth in claim 1 in which resilient means are provided normally urging said harness to its lowermost position.

6. The control device set forth in claim 2 in which a slide is positioned in the path of movement of the pivotal junction between said intermediate portions of said transmission element, said end portions and said intermediate portions being in substantially longitudinal alignment 60 when the pivotal portion between the intermediate portions is restrained by said slide and an electromagnet operably connected to said slide to actuate the latter.

7. The control device set forth in claim 6 in which resilient means normally urge said slide out of the path of

said pivotal junction, said electromagnet when energized moving said slide in the path of movement of said intermediate junction.

8. The control device set forth in claim 2 in which an abutment member is carried by one of said intermediate portions adjacent the pivotal junction therebetween, a fixed member having an abutment surface, a slide having an abutment surface, means to move said slide between one position in which it is in juxtaposition with said fixed member to define a continuous abutment surface, and a second position in which the abutment surface of said slide and said fixed member are spaced, to define a clearance space for the abutment member carried by one of said intermediate portions.

9. A control device for a transmission having movable thread guide means, comprising a vertically movable harness, a tongue depending from said harness, a lever pivotally connected between its ends to the lower end of said tongue, resilient means operatively connected to said harness to urge the latter to its lowermost position, a pair of transmission elements each comprising an upper push rod and a lower push rod, means maintaining said push rods in longitudinal alignment, means pivotally connecting the upper ends of the upper push rods to the ends of said lever, a pair of links defining a deformable portion 25 between adjacent ends of each of said upper and lower push rods, said links being pivoted to each other and pivoted at their free ends to the lower and upper end of the associated upper push rod and lower push rod, a slide member associated with each of said pair of links and 30 means to move said slide member into alignment with said links to restrain the latter in substantially vertical position and out of alignment with said links to permit bending of said links.

10. A control device for a machine having movable 35 thread guide means comprising a harness having a plurality of heddles, means mounting said harness for reciprocable movement, a pair of transmission elements each operatively connected to said harness and independently reacting thereagainst, each transmission element comprising 40 a pusher member having a deformable portion be-

tween its ends, means to vary the length of each deformable portion, and actuating means reacting against each of said pusher members to reciprocate the latter, whereby upon reciprocation of each transmission element by the associated actuating means, depending upon the setting of the associated deformable portion of each transmission element, the harness may be moved between a high and low position.

11. A control device for a machine having movable thread guide means comprising a harness having a plurality of heddles, means mounting said harness for reciprocable movement, an actuating lever, means operatively connecting said lever to said harness to reciprocate the latter, a pair of transmission elements each operatively connected to said lever at each end thereof, each transmission element comprising a pusher rod having a deformable portion between its ends, means to vary the length of each of said deformable portions and actuating means reacting against each of said pusher rods to reciprocate the latter, whereby upon reciprocation of each transmission element by the associated actuating means, depending upon the setting of the associated deformable portion of each transmission element, the harness may be moved between a high and low position.
